UNITED STATES PATENT OFFICE.

OTTO H. ERICKSON, OF MINNEAPOLIS, MINNESOTA.

ARTIFICIAL LEG.

1,405,191.

Specification of Letters Patent.

Patented Jan. 31, 1922.

Application filed November 29, 1920. Serial No. 426,956.

To all whom it may concern:

Be it known that I, OTTO H. ERICKSON, citizen of the United States, residing at Minneapolis, in the county of Hennepin and State of Minnesota, have invented certain new and useful Improvements in Artificial Legs; and I do hereby declare the following to be a full, clear, and exact description of the invention; such as will enable others skilled in the art to which it appertains to make and use the same.

This invention relates particularly to artificial legs of the type required for thigh amputations, and wherein the lower leg section is connected to the socket or upper leg section by a knee joint. The invention is directed chiefly to improved means for producing forward swinging movement of the lower leg section from the shoulder straps.

Generally stated, the invention consists of the novel devices and combinations of devices hereinafter described and defined in the claims.

In the accompanying drawings which illustrate the invention, like characters indicate like parts throughout the several views.

Referring to the drawings:

Fig. 1 is a front elevation of the improved leg;

Fig. 2 is a side elevation thereof;

Fig. 3 is a vertical section showing the ankle pivot for connecting the foot to the lower leg section, said foot and lower leg section being indicated by dotted lines only;

Fig. 4 is an enlarged fragmentary vertical section through the knee joint;

Fig. 5 shows the lower leg section and a portion of the socket or upper leg section chiefly in rear elevation, but with some parts in section;

Fig. 6 is a section on the line 6—6 of Fig. 1;

Fig. 7 is a section on the line 7—7 of Fig. 5, some parts being in full;

Fig. 8 is a side elevation illustrating a slightly modified arrangement of the leg-operating connection, some parts being broken away;

Fig. 9 is a front elevation of the leg shown in Fig. 8, but with some parts sectioned and with the thigh socket removed from the connection with the knee block; and

Fig. 10 is a front elevation of the knee block and thigh socket shown in Fig. 8, some parts of the latter being broken away.

The lower leg section is provided with a

foot 12 pivotally connected thereto by any suitable means, such as shown in Figs. 3 and 7, wherein the numeral 13 indicates a tubular pivot sleeve provided with nut-equipped stems 14 that anchor it to the lower leg section. The numeral 15 indicates a nut-equipped stem or bolt that is anchored to the foot 12, and has an eye pivoted on the central portion of the stem 14. The numeral 16 indicates a coiled compression spring seated in recesses in the lower portion of the leg section 11 and in the heel of the foot 12, and adapted to be adjusted by a screw 17 that works through a nut 18 anchored in the foot.

The spring 16 tends to rock the toe of the foot up, and this movement is adjustably limited by a stop screw 19 that works through a nut 20 anchored in the lower front portion of the leg section 11 and impinging on a small bearing plate 21 on the recessed top portion of the foot. By adjustments of the stop screw 19, the upward movement of the toe of the foot may be variably limited so as to give the right walking action for the particular person to whom the leg is applied.

The lower leg section 11, except at its lowermost portion, is hollow, and at the extreme upper portion of its sides, it is provided with rigidly secured hinge straps 22 through which is passed a tubular knee joint pivot bolt 23, that is headed at one end and provided with a cap screw 24 at its other end.

The thigh socket or upper leg section 25 is provided at its lower end with a knee block 26 that is pivoted on the knee joint pivot bolt 23, and, as shown, is provided with an inset metal bushing 27 that directly engages the same. The lower portion of the knee block projects down into the upper end of the lower edge section 11 and this block is provided with a vertical slot 28. The pivoted portion of the block 26 is considerably narrower than the space between the hinge straps 22, so as to leave space for its laterally spaced pairs of cord guide sheaves 29 and 30 that are loosely journaled on the end portions of the pivot bolt 23 just inward of said straps 22.

The numeral 31 indicates a non-elastic but flexible stop cord or strap, the upper end of which works in the slot 28, of the knee block 26 and is anchored to the rear portion thereof by a pin 32. The lower portion of the stop cord 31 extends downward into the

lower leg section 11 and is secured to the yoke of a U-bolt 33, which, in turn, is extended through an anchor bar or lug 34 on the rear portion of said leg section 11, and 5 is made adjustable by a nut 35. By adjustments of the nut 35, the anchor bolt 33 may be adjusted so as to cause the stop cord or strap 31 to limit the forward swinging movement of the lower leg section 11, as may 10 be desired to produce the best walking action for the particular person wearing the leg.

So far as this invention is concerned, the upper leg portion or thigh socket may be of any suitable form, but in the drawings it is 15 shown as of the type disclosed and claimed in my prior Patent No. 1,302,336, of date, April 29, 1919, and wherein the thigh socket 25 is adjustably connected to the knee block 26 by threaded engagement at 25^a (see particularly Fig. 9).

The customary shoulder straps 36 are attached to shoulder strap cords 37 located, one on each side of the leg. The looped lower portions of these cords 37 extend 25 down on the upper sides of the thigh socket 25, and thence, through guide sheaves 38, in the knee block 26, to the interior of the lower leg section 11, where they are passed under grooved guide sheaves 39 journaled to brackets 40 located, one on each side of the interior of the lower leg section. The two 30 upwardly extended branches of each cord 37 extend one over each of the guide sheaves 29 and 30. The cords 37 are adapted to 35 work through guide loops 41 on the upper portion of the thigh socket 25.

The construction illustrated in Figs. 8, 9 and 10 is like that already described, except for the fact that the guide sheaves 29^a and 40 30^a, which correspond to the guide sheaves 29 and 30 of the previously described arrangement, are journaled in pairs, one ahead of the other, on the opposite sides of the knee block 26, and except, also, for the further fact that the above described stop cord or strap 31 and its adjustable anchor bolts are arranged in duplicate.

It will, of course, be understood that in the buckling action the forward swinging movement of the lower edge section is produced 50 partly by gravity, but chiefly by upward strain on the shoulder straps 36 and cords 37. Inasmuch as the cords 37 run against the front portions of the guide sheaves 29 and 30, it is evident that the pull on the cords, being forward of the axis of the pivot bolts 23 will produce the said forward swinging movement of the lower leg section, and as the cords run over the said sheaves independently, the friction on the pulling action 55 will be reduced to a minimum. Moreover, by running the cords down through the knee block into the interior of the lower leg section, they are protected so that they 60 will not catch underwear and their move- 65

ments will not be interfered with by outside interference.

The arrangement of the bolts as best shown in Figs. 8 to 10, gives a greater forward pull on the lower edge section than 70 does the arrangement shown in Figs. 1 to 6, but the general action is the same in both constructions.

What I claim is:

1. In an artificial leg, the combination 75 with upper and lower leg sections pivotally connected by a knee joint, guide sheaves on the lower portion of said upper leg section and on the interior of said lower leg section, shoulder straps and cords guided on the exterior of said upper leg section, extended over the guide sheaves on said upper leg section into the lower leg section and under the guide sheaves on the interior of said lower leg section, said guide cord operating 80 on said sheaves to produce a forward swinging movement of said lower leg section.

2. In an artificial leg, the combination with upper and lower leg sections pivotally connected by a knee joint, guide sheaves on 90 the lower portion of said upper leg section and on the interior of said lower leg section, shoulder straps and cords guided on the exterior of said upper leg section, extended over the guide sheaves on said upper leg section and under the guide sheaves on the interior of said lower leg section, said guide cord operating on said sheaves to produce 95 a forward swinging movement of said lower leg section, and a stop strap connecting said 100 upper and lower leg sections at the rear of the knee joint.

3. In an artificial leg, the combination with upper and lower leg sections, the former having a knee block, a knee joint pivot bolt 105 connecting said lower leg section to said knee block, guide sheaves on the interior of said lower leg section, guide sheaves on said knee block having portions that are forward of the axis of the knee joint, and 110 shoulder straps and cords, the latter extending from the exterior of said upper leg section, through joints in said knee block over the sheaves on said knee block and under the sheaves on the interior of said 115 lower leg section.

4. An artificial leg comprising upper and lower leg sections, the former having a knee block that is reduced in width so that it fits within the upper portion of said lower 120 leg section with clearance from the sides thereof, a knee joint pivot bolt pivotally connecting said knee block to the upper portion of said lower leg section, pairs of guide sheaves mounted on said pivot bolt between the reduced sides of said knee block 125 and the sides of said upper leg section, sheaves on the interior of said lower leg section, and shoulder straps and cords, the latter extending from the exterior of said 130

upper leg section, through joints on said knee block, over the sheaves on said pivot bolt, and under the sheaves on the interior of said lower leg section.

5 5. In an artificial leg, the combination with upper and lower leg sections, the former having a knee block pivotally connected to said lower leg section by a knee joint

pivot, guide sheaves on said knee block, and shoulder strap cords extended through 10 guides on said knee block and over the guide sheaves thereon and acting on the lower leg section to swing the same forward under upward strain on said cord.

In testimony whereof I affix my signature. 15
OTTO H. ERICKSON.
